UNITED STATES PATENT OFFICE.

HERMAN BAHR, OF LITTLE FALLS, NEW YORK.

METHOD OF PICTORIAL REPRODUCTION.

Application filed August 1, 1922. Serial No. 578,885.

To all whom it may concern:

Be it known that I, HERMAN BAHR, a citizen of the United States, residing at Little Falls, in the county of Herkimer and State of New York, have invented certain new and useful Improvements in Methods of Pictorial Reproduction, of which the following is a specification.

My invention relates to methods of pictorial reproduction.

The invention pertains particularly to a method of forming from a given pictorial object a foraminous stencil, from which cut-out stencils are made for emphasizing or coloring given portions of the pictorial design. I am aware that it is not generically new to form a foraminous stencil photographically, but it is my belief that the particular method pursued and the additional steps included are novel.

In carrying out my invention, I provide a pictorial design from which a photographic negative is made, either on a plate or a film, and a foraminous screen treated with sensitive material and exposed through said negative, the exposed portions hardening, and the unexposed portions being soluble, and are washed out by hot water or steam, and which screen after drying is varnished to strengthen the hardened emulsion in the screen.

From this foraminous stencil thus made, reproductions of the pictorial design may be produced, and, as a further part of my invention, I reproduce a plurality of designs on a given material from which the essential parts are cut, so that any desired portion of the outline, which it may later be desired to emphasize or to color may be safely treated through the cut-out portions of said stencils. This will be quite clear when taken in connection with the accompanying drawings, in which:—

Fig. 1 is a plan view of a sketch or drawing involving a pictorial design to be reproduced by my method;

Fig. 2 is a similar view of the photographic negative made therefrom.

Fig. 3 is a plan view of a frame upon which the fine meshed material is stretched, and upon which the sensitive material is placed before exposure to the negative;

Fig. 4 is a similar view of the meshed fabric after exposure, and after the unexposed portions have been washed and the screen has been varnished;

Fig. 5 is a plan view of the pictorial design reproduced through the foraminous stencil similar to the original as shown in Fig. 1;

Fig. 6 is a view of a stenciled figure reproduced on suitable material, and from which desirable parts are cut to form a cut-out stencil for emphasizing or coloring a desired portion of the design;

Figs. 7 and 8 are similar views with different cut-out portions; and

Fig. 9 is a view of a reproduction on material such as felt, and which has been colored in a desired manner by the use of the cut-out stencils shown in Figs. 6, 7 and 8.

The drawing or other pictorial design 14 on the card 15 may be of any desired color or proportions, and is photographed in any desired manner so as to make the negative 16 upon which the design appears as at 17. A frame 18 open at both sides has tacked to it the mesh fabric 19 which is stitched tightly across it, and upon which a suitable emulsion (not shown) is placed.

I prefer to use as a sensitive emulsion for this purpose, a mixture consisting of one part gelatine, two parts fish-glue, with enough ammonium bichromate to turn a deep orange. The emulsion is spread over the fine mesh of the screen, and is dried in a suitable manner, such as over a heater of some sort. Then the negative is placed in the box formed by the frame. The sensitive screen is then exposed to sunlight or strong artificial light. The action of the light is to harden the exposed portions 20 to render or to leave soluble the unexposed portions 21 shown in Fig. 4. The screen is then washed with hot water or steam, and the soluble portions are washed out. The screen is then dried and varnished, or paint is applied to the screen, which strengthens the hardened emulsion 20 in the screen. As indicated in Fig. 4, the effect is to reproduce the original pictorial design 14 on the screen, the outline by hardened emulsion, and the essential parts of which design are simply a fine mesh through which pigment or paint or ink or other suitable coloring matter may be projected. The result is as indicated in Fig. 5, where the pictorial effect 22 is produced on the card or paper 23.

In order to simulate hand-painting, I carry the process further by projecting through the foraminous stencil on a suitable oiled cardboard 24 a reproduction 25 of the pictorial design, which may be by white

- paint or any other suitable coloring, and cut from such cardboard stencils portions 26 which, as shown in Fig. 6, might be a cheek and the mouth which it is desired to 26 tint pink, and, as shown in Fig. 7, the hair 27, and, as shown in Fig. 8, it might be the entire face and neck 28. Obviously the ones selected are purely illustrative, and any other form might be used.
- 10 In order to reproduce the design in colors on a suitable felt base, or other more or less absorbent composition, the foraminous stencil is used, and the outline of the figure might be projected and strained through 15 the screen to form a figure as shown in Fig. 5. Then in order to tint the figure against the preferably colored background of the felt 29, the cut-out stencil shown in Fig. 8 is used to give a different color to 20 the face and neck. The stencil shown in Fig. 7 may be used to give a desirable tone to the hair, and the stencil shown in Fig. 6 could then be used to give a touch of pink or red to the checks and lips of the figure.
- 25 The effect, as shown in Fig. 9, is that of a hand-painted figure on the colored background, but which can be easily and quickly made, and is not subject to the vagaries of the artist, such as would be the case were 30 it to be hand-painted.
- The invention may be used to reproduce or reprint any pictorial design whatever, and it is further useful in the reproduction of negatives from the foraminous stencil; 35 such negatives may be made by reproductions or impressions on transparent paper, tracing-cloth, or films, which thereby saves a great deal of expense now necessary in the production of photographic negatives;
- 40 and, further, the negatives thus obtained may be used with great success in turning or reversing designs used.
- Obviously many modifications or changes will occur to those skilled in the art, and I 45 do not wish to be considered as limited in any way to the precise disclosure made herein.
- I claim as my invention:—
1. A method of simulating a hand-painted pictorial design, which consists in forming an original design, creating a foraminous

stencil therefrom, forming cut-out stencils 55 from said foraminous stencil, and coloring predetermined portions of the design with a desirable tint by said cut-out stencils.

2. A method of simulating a hand-painted pictorial design, which consists in forming an original design, making a photographic negative therefrom, exposing the sensitized foraminous screen through said negative, washing out the unexposed portions of the emulsion, varnishing the screen to strengthen the hardened emulsion reproducing the design on stiffened material, cutting out from said reproduced design portions it is desired to tint, reproducing on the absorbent material a design from said foraminous 70 stencil, and tinting said design from said cut-out stencil.

3. A method of producing cut-out stencils which consists in producing an original design, reproducing the design in a foraminous 75 stencil, and reproducing the design from the foraminous stencil on secondary stencil material from which desirable portions are cut.

4. A method of producing an accentuated or tinted design upon material which consists of producing a plurality of identical designs upon stencil material, cutting out from said material certain portions of the design which it is desired to tint or to accentuate reproducing the design upon a desired material and tinting or accentuating desired portions thereof by successively imposing and using desired cut-out stencils upon such material.

A method of accentuating or tinting a 90 pictorial design upon material which consists in producing the complete design upon a foraminous stencil, producing a plurality of successive prints of said design through the foraminous stencil upon sheets 95 of secondary stencil material, cutting out from each of such reproduced designs a portion to be accentuated or tinted in the finished print, then reproducing the design upon material and tinting or accentuating desired portions thereof by means of such secondary cut out stencils.

In testimony whereof I affix my signature.

HERMAN BAHR.
